(57) **CLAIM**

We claim the ornamental design for a bracket for digital photo frame, as shown and described.

DESCRIPTION

FIG. 1 is a perspective view of a bracket for digital photo frame showing our new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof;

FIG. 7 is a bottom plan view thereof;

FIG. 8 is a perspective view thereof before combined with a digital photo frame; and,

FIG. 9 is a left-side elevation view thereof being installed on a digital photo frame.

The dash-dot broken lines in FIGS. 8 and 9 are included for the purpose of illustrating environment and form no part of the claimed design.

1 Claim, 6 Drawing Sheets
